VACUUM FLUID LIFT

Luther J. Campbell, Hobbs, N. Mex., assignor to
E. B. Gilmore, Oklahoma City, Okla.Application February 28, 1934, Serial No. 713,396
Renewed September 10, 1935

3 Claims. (Cl. 103—232)

The invention relates to a vacuum fluid lift and more especially to a lift for use in oil wells.

The primary object of the invention is the provision of a device of this character, wherein fluid within a well will be lifted under the action of an impeller, the same being driven by gas or air under pressure, the impeller being provided with a blade formation or a spiral which reduces friction to a minimum and causes a force to radiate outwardly toward the outer edge of the blade or spiral, thereby increasing the work performed on the impeller and at the same time increasing the velocity of the flow therethrough, so that a constant flow is assured, with the result that a steady stream of fluid will be brought to the surface, with elimination of the heads usually encountered with the general air or gas lifts.

Another object of the invention is the provision of a device of this character, wherein the assembly is such as to avoid close fitting parts with resultant rapid wear thereof and necessitating frequent repairs, there being a fluid seal between the blade or spiral of the impeller and the wall of its working barrel, and the disposition of the blade or spiral is such that all components of energy are converted into centrifugal force when leaving the impeller, and friction being reduced to a minimum assures a steady and constant flow of fluid for the lifting thereof from within a well.

A further object of the invention is the provision of a device of this character, which is extremely simple in construction, thoroughly reliable and efficient in its purposes, durable, economical in the upkeep, and inexpensive to manufacture and install.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereinto appended.

45 In the accompanying drawing:

Figure 1 is a side elevation of a fluid lift device constructed in accordance with the invention and the same being partly in vertical section.

Figure 2 is a top plan view thereof.

50 Figure 3 is an enlarged sectional view on the line 3—3 of Figure 1 looking in the direction of the arrows.

Figure 4 is a fragmentary enlarged vertical sectional view through the eduction pipe or working barrel and the impeller.

Similar reference characters indicate corresponding parts throughout the several views in the drawing.

Referring to the drawing in detail, the fluid lift device comprises a tubular working barrel or eduction pipe 10 having arranged therein an impeller 11 which, at its lower end, has integral therewith a thrust annulus 12, while the lower extremity of the arbor of this impeller is of tapered formation, as at 13, and slightly protrudes beyond said annulus 12, the barrel or pipe 10 being threaded into a coupling 14 which is also joined with an ejector 15 of any conventional type having the side nipple 16 for union with a fluid conduit (not shown).

Arranged parallel with the barrel or pipe 10, at one side thereof, is an air or gas feed pipe 17 which at its lower end, through the L unions 18 and 19, respectively, has connection and communication with and through the lower end of 20 the ejector 15.

The pipe 10 at the end 20 joined with the coupling 14 forms interiorly of the latter a shoulder between which and the annulus 12 of the impeller 11 is arranged an antifriction thrust bearing 21 for said impeller 11, the upper end of the impeller being free and terminating flush with the upper open end of the barrel or pipe 10, as will be apparent from Figure 1 of the drawing.

The impeller 11 has a spiral or screw-like blade formation 22, the working surface 23 or the side thereof which the vertically moving flow collar impinges upon having a taper from one-quarter inch to one-sixteenth inch from the arbor to the outer edge, and this outer edge being made a tangent to the outer cylindrical area of the barrel or pipe 10, so that a high velocity column of gas or gas and air and liquid issuing from the ejector 15 impinges on the spiral or screw formation of the impeller 11, so that the full extent thereof will be utilized in throwing the fluid out radially and the centrifugal force will be at a maximum so that the upward thrust of the force from the ejector acting on the spiral or screw formation will cause the annulus 12 to 45 thrust against the bearing 21 and friction will be reduced to a minimum, so that all components of energy are converted into centrifugal force when leaving the impeller. The centrifugal motion of the fluid mixture when leaving said 50 impeller is a free vortex flow, rendering the device a constant flow tool and bringing the fluid to the surface in a steady stream, the vacuum created by the device both at the point of entrance to the ejector 15 and the motion of the 55

impeller within the barrel or pipe 10, as well as the motion of the fluid, eliminating back pressure.

The ejector in the working thereof is the source of driving energy for the impeller 11 and the pressure of the feed of fluid from the pipe 17 to the ejector 15 directs the liquid into the path of the impeller for the lifting operation of such liquid or the mixture of the fluid and liquid, the 10 fluid being either gas or air.

The spiral or screw formation of the impeller reduces friction to a minimum, this being by reason of the back of the spiral or screw formation being made a tangent to the true circle of the barrel or pipe 10, while the taper of such spiral or screw formation at the working side of the same should tend to cause the force to radiate outwardly toward the outer edge of said spiral or screw formation, with the result of an 15 increase in the velocity of the flow of fluid through the impeller and the diversion of all 20 force into a greater radius in this outward direction.

The working side of the impeller is tapered or 25 rounded off to a degree that there will be virtually no impact of the fluid pressure upon a flat or normal plane, this taper or rounding being on the outside of the blade of the impeller or that side of its blade which is a tangent to the 30 true cylindrical area. As has been stated, the ejector 15 in the coupling for the fluid supply 35 through inlet 16 is of a conventional kind and the discharge nozzle of said ejector, as indicated at 24, discharges its fluid pressure directly upon the blades of the rotor 11. The gas feed pipe 17 runs up alongside the barrel or pipe 10 to which it is 40 adapted to be strapped to a point above the static fluid level in the well and terminates at this end in a perforated nipple (not shown). Gas or air or both are pumped into the annular space between the tubing or the small string of pipe 45 which is used to carry the fluid to the surface and the casing, where sufficient pressure is built up to start the flow through the device, the pressure passing downward through the pipe 17, street elbows 18 and 19 and the ejector 15. The 50 kinetic energy developed in the nozzle of the ejector 15 creates a suction or vacuum at the inlet 16 and, as stated above, the fluid pressure passing from the discharge nozzle of the ejector impinges directly on the blades of the impeller 11 which converts all components of energy into 55 centrifugal force upon leaving the same.

The solid liquid to be pumped is drawn in 55 through the inlet 16 and mixed with the gas or air or both in the discharge nozzle 24 of the ejector 15 and is discharged against the blades of the impeller 11, and, of course, into the barrel 10, or, in other words, is discharged directly 60 into the vanes of the said impeller.

For all practical purposes the impeller 11 should have not less than ten complete spirals and the barrel 10 can extend beyond or above the said impeller and is adapted for pipe coupling, as it 65 becomes only a part of the flow string of the pipe

beyond the impeller. However, no fixed length for the impeller can be stated, as for pumping fluid from great depths it might be advisable to use a longer impeller, depending, of course, upon several factors, namely, the diameter of the 5 pump that would be most economical for the specific installation considering the amount of fluid to be lifted, the depth to be lifted and the conservation of the lifting energy. The diameter of the impeller 11 governs the length of the same 10 for any given number of spirals, that is to say, a rotor three inches in diameter with blades constructed on an angle of forty degrees and having ten complete spirals would be much longer than one constructed likewise and being only one 15 and one-half inches in diameter.

What is claimed is:

1. A device of the character described comprising a working barrel, a spirally bladed impeller within said barrel, an ejector in advance of 20 the impeller, a coupling joining the barrel and ejector, a thrust annulus formed at the end of the impeller next to the ejector, a thrust bearing between the annulus and the working barrel next thereto, a fluid feed pipe communicating with the 25 ejector at the lowermost end thereof, and means for delivering liquid into the ejector at one side thereof, the working side of the blade of the impeller being tapered from the arbor of said impeller to the outer edge of said blade and disposed 30 at a tangent to the outer cylindrical area of the barrel.

2. A device of the character described comprising a working barrel, a spirally bladed impeller within said barrel, an ejector in advance 35 of the impeller, a coupling joining the barrel and ejector, a thrust annulus formed at the end of the impeller next to the ejector, a thrust bearing between the annulus and the working barrel next thereto, a fluid feed pipe communicating with the 40 ejector at the lowermost end thereof, means for delivering liquid into the ejector at one side thereof, and a working surface formed on the blade of the impeller at a tangent to the outer circular formation of the barrel, the said working 45 surface further being angled from the arbor of the impeller to the outer edge of said blade.

3. A device of the character described comprising a working barrel, a spirally bladed impeller within said barrel, an ejector in advance 50 of the impeller, a coupling joining the barrel and ejector, a thrust annulus formed at the end of the impeller next to the ejector, a thrust bearing between the annulus and the working barrel 55 next thereto, a fluid feed pipe communicating with the ejector at the lowermost end thereof, means for delivering liquid into the ejector at one side thereof, a working surface formed on the blade of the impeller at a tangent to the outer circular formation of the barrel, and a downwardly tapered lower terminal at the center of said 60 impeller to be disposed in confronting relation to the ejector.
